UNITED STATES PATENT OFFICE.

LEE H. GEISENDORFF, OF INDIANAPOLIS, INDIANA, ASSIGNOR OF ONE-HALF TO
FRANK M. FAUVRE, OF INDIANAPOLIS, INDIANA.

COMPRESSOR.

1,168,625.

Specification of Letters Patent. Patented Jan. 18, 1916.

Application filed January 12, 1914. Serial No. 811,627.

To all whom it may concern:

Be it known that I, LEE H. GEISENDORFF, a citizen of the United States, residing at Indianapolis, in the county of Marion and State of Indiana, have invented certain new and useful Improvements in Compressors, of which the following is a specification.

In the manufacture of compressors for compressing anhydrous ammonia gas the 10 elimination of leakage of gas has always been a serious proposition, involving both a matter of expense and the surrounding obnoxious atmospheric conditions incident to such escaping gas, the above causes prohibiting the introduction of refrigerating systems 15 for domestic purposes.

The object of the present invention contemplates the embodiment of certain features for a compressor to be used in refrigerating systems for domestic purposes, 20 wherein anhydrous ammonia gas can be compressed without waste, the parts being constructed that in case of leakage of gas from the compression cylinders same will 25 be caught, conserved and returned to the circulating system, and thereby through efficient and economical service rendered, a demand will be created for the installation 30 of refrigerating systems for domestic purposes.

A further object of the invention consists in the provision of a compressor of the above specified class, wherein the housing in addition to providing a reservoir for holding the 35 lubrication for the rotative parts, also serves as a chamber for conserving such gas as may escape from the compression cylinders.

A further object of the invention consists in the provision of a compressor of the above 40 specified class wherein the usual packing glands employed around the piston rods and near the point of compression are dispensed with, a single packing gland alone is used and is remotely situated where it is less 45 liable to be affected by heat incident to the high compression of the gas, this single packing gland being the only one required in the entire compressor.

A further object of the invention is to provide 50 a compressor of the above character wherein each piston may be individually adjusted with respect to the adjacent cylinder head, thereby insuring that all gas will be ejected from the cylinders at each stroke of 55 the pistons, thereby securing the highest

possible capacity and efficiency for the size of the compressor employed.

A further object of the invention is to provide a compressor of the above character wherein the cylinders are formed independently of the compressor housing so that cylinders with larger bores, with a correspondingly increased capacity, may be employed without disturbing or changing the remaining parts of the compressor. 60

A further object of the invention consists in the provision of a compressor of the above character wherein the piston rings are mounted independently of the pistons in order not to disturb their trueness when 65 placing them on or removing them from the pistons, whereby greater packing efficiency is secured between the pistons and cylinders. 70

I accomplish the above objects of the invention by means of the construction illustrated in the accompanying drawings, forming a part hereof, in which—

Figure 1 is a view partly in side elevation and partly in section of my improved compressor, in which the side-plate of the housing is omitted to expose the assembled condition of the internal mechanism of said compressor, on the dotted line 1—1 in Fig. 2. Fig. 2 is a horizontal sectional view on the line 2—2 in Fig. 1. Fig. 3 is a fragmentary detail sectional view, on a considerably enlarged scale, showing the construction and arrangement of the inlet and outlet valves for the ammonia gas and their connection with the cylinders of the compressor. 80 Fig. 4 is an external view of the means for retaining the valves firmly within the cylinder heads. Fig. 5 is a side elevation of an L-shaped ring and a piston ring. Fig. 6 is a fragmentary detail view in side elevation of 85 one of the piston rods showing them constructed so as to render them self-centering in the cam yoke. 90

Referring to the drawings, 10 represents the central housing of the compressor, which 100 is mounted upon a suitable base 11. The central portion of the housing 10 is hollow and provides, first, working room for the internal movable parts of the compressor, and, second, a chamber to catch and conserve 105 such gas as may escape from the cylinders.

12 represents the main driving shaft which passes transversely through the housing 10 and through a suitable packing gland 13 within the cup 14 formed integrally on 110

the side-plate 15, of the housing, the other end of the shaft projecting into a socket 16 formed integrally with the side-plate 17. The shaft 12 is provided with a suitable pulley 18 to which power from any suitable power generator, particularly an electric motor, is imparted for operating the generator. Communicating with the internal chamber of the compressor housing and at right angles to the shaft 12 are the hollow cylinders 20. These cylinders are provided on their outer ends with an annular rib 21 which rest in corresponding grooves 22 in the outer ends of the sleeves 23, and the said sleeves are secured to the housing 10 by means of suitable bolts 24. The inner ends of the cylinders 20 are reduced in diameter to form the shoulders 25 which rest within recesses 25^a in the housing 10, and suitable joints between the two are effected by means of the gaskets 26, so that leakage is prevented. The cylinders 20 are held in rigid relation within the sleeves 23 by means of the cylinder-heads 30 which seal the outer ends of the cylinders, and the heads 30 also provide means for locating the inlet and outlet valves for controlling the flow of ammonia gas to and from the cylinders. The cylinders 20 are provided with extremely thick walls, enabling them to be re-bored in case of undue wear, so that the life of said cylinders is materially prolonged. The cylinders 20 are also formed independently of the housing 10 which enables them to be removed and cylinders with larger bores substituted whereby the capacity of the compressor may be increased without necessitating change in other parts of the compressor. From a manufacturing standpoint this is of particular importance. As the compression reaches about two hundred pounds to the square inch within the cylinders 20 the latter may become heated and expand sufficiently to interfere with the operation of the pistons, and to eliminate trouble from this source, I provide means for keeping the cylinders cool. This is accomplished by means of the chambers 35 located between the peripheries of said cylinders and the sleeves 23, said chambers extending circumferentially around said cylinders, and by means of inlet pipes 38 and outlet pipes 39 streams of water may be constantly passed through said chambers to extract heat produced by compression.

The pistons comprise members 40 the diameters of which coincide with the internal diameters of the cylinders 20, and these members 40 are reduced in diameter on their forward ends, as shown, to receive a plurality of L-shaped collars or rings 41, and these collars form seats for the piston rings 42. The rings 42 are held against accidental displacement by means of the caps 43 and lag-screws 44 which pass through the caps

and into the end of the pistons. This construction serves the purposes, first, it enables the rings to be truly turned to fit the internal diameters of the cylinders and be placed upon the L-shaped rings 42 without expanding them, as now obtains in cylinders having circumferentially disposed grooves for the reception of the piston rings, and second, the collars and rings may be easily removed and replaced without removing the cylinders 75 and pistons.

The pistons 40 are reciprocally actuated in their respective cylinders through the piston rods 54 by means of a single cam 50 which is keyed fast to the driving shaft 12, 80 and this cam engages an opening centrally located within a block 51 having vertical travel, the travel of said block being limited by means of a yoke 53 which is reciprocated in a plane at right angles to that of the block 51 and parallel with a plane passing through the longitudinal axis of the cylinders. Rotation of the yoke 52 is prevented by means of suitable guides 53^a upon which the yoke rides. Examining Fig. 2 of the drawings, 90 it will be noted that the yoke 53, block 51 and cam 50 are easily assembled and held in operative relation by the side-plate 17 of the housing. This construction contemplates the use of a flange 51^a formed integrally with 95 and extending around the outer marginal edge of the block 51, and this flange bears against the face of the yoke 52 and limits the insertion of the block therein. The cam 50 is provided with a flange 50^a, similar to the flange 51^a, which rests against the face of the block 51 and limits the insertion of the cam therein, so that with the side-plate 17 of the housing bearing against the hub of the cam 50, the said cam and block 51 are 105 operatively held together with the yoke 53.

In compressors in common use the pistons pass through packing glands, and as the reciprocating movement of the pistons soon destroys them and, to prevent leakage, constant re-packing of the glands is necessary, which is expensive. In my improved compressor these packing glands are dispensed with, but one gland being used on the main driving shaft 12 where it is not affected by 115 heat and is not required to withstand the effect of high compression within the cylinders, so that the gland will stand long usage without attention. The piston rods 54 are rigidly secured to and moved with 120 the yoke 53, the latter being provided on its opposite sides with integrally formed ears 55 to form seats for said piston rods. The ears 55 have a transverse central opening for the reception of the nuts 56 mounted on the inner ends of the piston rods 54. Apertures 57, in the ears 55 on the sides adjacent to the cylinders to receive the piston rods 54, are cone-shaped, as shown in Fig. 2 of the drawings, and nuts 60 are pro- 125 130

vided with cone-shaped enlargements 58 (see Fig. 6) which engage the cone-shaped portions of the apertures 57. By means of this construction the piston rods 54 are 5 easily centered to register with a plane passing through the longitudinal axis of the cylinders 20, and also lending an easy adjustment of the pistons 40 and regulating their travel with respect to the cylinder 10 heads. The outer ends of the piston rods 54 pass through the longitudinal center of the pistons 40 and said rods are rigidly secured to said pistons by means of the nuts 61 and 62. When the cam 50 is rotated the 15 yoke 53 is reciprocated whereby one of the connected pistons is drawn inward within its cylinder to draw in a charge of gas while the piston on the other side of the yoke is moved toward the compression end of its 20 cylinder to eject the gas under compression. In order to obtain the highest working efficiency and capacity of the compressor it is necessary at all times to effectually discharge all gas from the cylinders at each 25 stroke of the pistons. This can only be accomplished by providing an individual adjustment for each piston whereby its head which, in this instance, is the cap 43, will be brought approximately against its cylinder head, and this is accomplished by adjusting the nuts 56 and 60 on the piston rods 54 against the yoke 53. In case the heads of the pistons were not brought approximately against the cylinder heads in 30 35 intervening spaces between the ends of the pistons and cylinder heads would result so that a portion of the gas under pressure would be retained in the cylinders, and on the return strokes the pistons would be 40 obliged to move a sufficient distance away from the cylinder heads to allow the compressed gas to expand sufficiently, with resulting reduction in pressure, until the resistance so offered would be overcome by 45 the springs in the inlet valves. This advance movement of the pistons would consume a substantial percentage of their travel within the cylinders so that the charges of the incoming gas would be correspondingly 50 reduced with a corresponding reduction in the capacity of the compressor.

The compressor is provided on each end with a piston head 30, as heretofore mentioned, and each piston head is provided 55 with a pair of valves one of which is an intake valve for allowing the anhydrous ammonia gas to pass into the cylinders of the compressor while the other valves allow the compressed gas to escape from the cylinders 60 of the compressor. Fig. 3 clearly illustrates the construction and arrangement of these valves in which the anhydrous ammonia gas is conveyed to the inlet valves through a pipe 70, which bifurcates, the 65 bifurcation ends leading to and connecting with the chambers 71 within the cylinder heads 30. The chambers 71 extend around the outer peripheries of the valves. The inlet valves comprise hollow cylinders 72 and these cylinders are provided with a 70 plurality of longitudinal slots 73 which communicate with the chambers 71 whereby the gas is let into the central bores of said valves. The valve stems 75 are arranged centrally within the cylinders 72 of the inlet valves and are provided on their lower ends with the integrally formed conical valves 76 which are seated in correspondingly formed openings in the ends of the valve cylinders 72. The outer ends of the 80 valve stems 75 are secured to the spiders 78 the diameters of which coincide with the internal diameters of the cylinders 72. Springs 79, resting against the bases 80 which act as guides for the valve stems 75, 85 also bear against the spiders 78, the tendency of said springs being to keep the valves 76 normally in their seats, but these springs offer little resistance so that the valves 76, stems 75 and spiders 78 are free to move 90 longitudinally within the cylinders 72 when the suction caused by the receding pistons is sufficient to overcome the resistance offered by said springs. When this occurs an intake of gas is drawn into the cylinders. 95 To allow the gas to escape under compression from the compression cylinders, I provide valves comprising the cylinders 90 similar to the cylinders 72. In this instance the valve-stems 91 pass freely through the 100 spiders 92, these spiders being threaded into the outer ends of the cylinders 90. Each of the valve-stems 91 is provided with a second spider 93 which is secured to and moves with the stems, and springs 96 are mounted between the spiders 92 and 93, the tendency of 105 said springs being to hold the valves 97 normally in their seats in the inner ends of the cylinders 90. When the pistons approach the cylinder heads the gas will pass 110 into the hollow cylinders 90 and through the longitudinal openings 98 therein, and through the discharge openings in the heads and through the outlet pipes 99. To prevent the gas from being dissipated through 115 leakage around the peripheries of the cylinders 72 and 90, forming the bodies for the inlet and outlet valves, I provide suitable bridge blocks 100. These blocks are provided with integrally formed lugs which 120 project into the openings in the heads 30 and receive the cylinders 72 and 90 of the valves. As shown, suitable gaskets 102 are inserted between the edges of the cylinders 72 and 90 and the bridge blocks, and tension 125 will be applied to the cylinders 72 and 90 by means of the bolts 103 which pass through the ends of the bridge blocks and into the cylinder heads 30. By turning the bolts 103 in the direction desired the bridge 130

blocks are forced toward the cylinder heads 30, thus enabling sufficient pressure to be applied on the gaskets 102 to seal the joints between the cylinders 72 and 90 and the 5 adjacent walls of the heads 30.

It has heretofore been pointed out that the central portion of the housing 10 forms a hollow chamber to provide working room for the internal mechanism of the compressor, and in addition thereto it forms a chamber to catch and confine such gas as may possibly escape from the cylinders, thus 10 acting as a reservoir for such gas. The gas so caught and retained in the housing is withdrawn therefrom and re-introduced 15 into the circulating system through a pipe 105 which communicates with the interior of the housing 10 and with the main supply pipe 69 which supply the pipes 70 that 20 carry the gas into the cylinder heads 30. The pipe 105 is provided with a suitable valve 106 whereby the movement of the gas from the housing 10 into the pipe 69 may be controlled.

25 While I have described my invention with more or less minuteness as regards details of construction and arrangement and as being embodied in certain precise forms, I do not desire to be limited thereto unduly 30 or any more than is pointed out in the claims. On the contrary, I contemplate all proper changes in form, construction, and arrangement, the omission of immaterial elements, and the substitution of equivalents, as circumstances may suggest or necessity render expedient.

Having thus fully described my said invention, what I desire to procure by Letters Patent, is—

40 1. In a double acting compressor the combination of two cylinders in axial alinement with each other, reciprocating pistons in said cylinders, a yoke connecting said pistons, a cam-block arranged in said yoke, 45 means on one side of said cam-block for limiting its introduction into said yoke, a revoluble cam, means on one side of said cam for limiting its introduction into said cam-block, and a single means for holding 50 said cam, cam-block and yoke in operative relation.

55 2. In combination with a double acting compressor housing, of two cylinders in axial alinement with each other, reciprocating pistons in said cylinders, a yoke connecting said pistons, a cam-block arranged in said yoke, means on one side of said cam-

block for limiting its introduction into said yoke, a revoluble cam, means on one side of said cam for limiting its introduction 60 into said cam-block, and a single means comprising a side wall of the compressor housing for holding said cam, cam-block and yoke in operative relation.

3. In a double acting compressor the combination of two cylinders in axial alinement with each other, reciprocating pistons in said cylinders, piston rods for the pistons, a yoke provided with conically shaped apertures adapted to receive the adjacent ends 70 of the piston rods, cone shaped means arranged on said piston rods adapted to engage the correspondingly shaped apertures in the yoke, and a single means for holding the cam, cam-block and yoke in operative 75 relation.

4. In a double acting compressor, an air tight hollow housing, a pair of alined compression cylinders communicating with said housing, reciprocating pistons in said cylinders, a yoke connecting the pistons together, a cam-block arranged in said yoke, means on one side of said cam-block for limiting its introduction into said yoke, a revoluble cam arranged in said cam-block, means on 80 one side of said cam for limiting its introduction into said cam-block, and means for establishing communication between said housing and cylinders.

5. In a double acting compressor, an air tight hollow housing, a pair of alined compression cylinders communicating with said housing, reciprocating pistons in said cylinders, piston rods for the pistons, a yoke provided with conically shaped apertures 90 adapted to receive the adjacent ends of the piston rods, cone shaped means arranged on the piston rods adapted to engage the correspondingly shaped apertures in the walls of the yoke for self centering said piston rods in axial alinement of said cylinders, 100 a single means for holding the cam, cam-block and yoke in operative relation, and means for establishing communication between said housing and cylinders.

105 In witness whereof, I have hereunto set my hand and seal at Indianapolis, Indiana, this 27th day of December, A. D: one thousand nine hundred and thirteen.
